TUBE COOLER

William J. Roberts and Samuel W. Traylor, Jr.,
Allentown, Pa., assignors to Traylor Engineering & Manufacturing Co., Allentown, Pa., a corporation of Delaware

Application September 10, 1942, Serial No. 457,890

1 Claim. (Cl. 257—94)

This invention relates to tube coolers of the general type in which the material to be cooled is passed in separate streams through a series of relatively thin-walled, heat-conductive muffle tubes mounted for rotation about a common axis inclined slightly out of horizontal while a cooling medium, such as air or water, or both, is directed into contact with the external surfaces of the tubes for cooling the material passing therethrough. Such type of apparatus is especially suitable for the cooling of materials, such as lime, that has a tendency to react with the air or the moisture in the air and which for that reason desirably should not be exposed to the atmosphere, and particularly when in a heated condition.

An important object of the present invention is to provide in a tube cooler of the above character means to accelerate the cooling of the material during its passage through the tubes. This object is accomplished according to the invention by providing means for drenching the tubes with cooling water as they rotate through a portion of their circular path of travel, the cooling action being further aided by evaporation of the moisture from the surface of the tubes as they move through another portion of their path of travel.

In the preferred form of the invention means are provided for applying the cooling water to the tubes in the form of a spray, or sprays, located below the cooler and so arranged as to discharge upon the bottom circumferential surfaces of the tubes as the tubes rotate through their lowermost arc of travel, whereby the water is effectively applied upon the hottest portions of the tubes, namely those portions which at the moment are overlain by beds of material inside the tubes.

Another object of the invention is to provide in a tube cooler of the above character means for bringing the material into more intimate contact with the cooling surfaces of the tubes. Under ordinary operating conditions in the case of tube coolers, the material tends to slide along the tubes in fixed masses so that portions of the material contained inside these masses do not come into contact with the cooling surfaces of the tubes and hence a longer time is required for cooling the material. To overcome this objection, the invention contemplates the provision of diaphragms extending lengthwise within the tubes and partitioning the tubes into a number of segmental compartments for dividing the mass of material traveling through the tubes

into streams of relatively small volume and for spreading the material out in the form of shallow layers, thus insuring that all portions of the material are brought into direct and effective contact with the cooling surfaces of the tubes.

Another function of the diaphragms is to shower the material from one diaphragm to another during rotation of the cooler, whereby a continuous stirring up and turning over of the material is achieved, resulting in the complete aeration and repeated exposure of all the particles to the cooling surfaces of the tubes. The diaphragms are preferably made of metal and arranged in heat-conductive relation to the circumferential walls of the tubes in order to increase the heat-transfer surface of the tubes and to conduct heat from the material on the inside of the tubes to the water-cooled walls of the tubes.

Other objects and advantages will be apparent from the following detailed description of a preferred embodiment of the invention, reference being had to the annexed drawings in which:

Figure 1 is a longitudinal cross-sectional view of a rotary, water-cooled tube cooler;

Figure 2 is a transverse cross-sectional view through the cooler taken on the line 2—2 of Fig. 1;

Figure 3 is a transverse cross-sectional view through one of the muffle tubes of the cooler, showing the arrangement of one of the diaphragm units therein;

Figure 4 is a contracted plan view of a diaphragm unit; and

Figure 5 is a plan view of a spray pipe assembly for directing cooling water onto the muffle tubes.

In the cooler shown in Fig. 1 of the drawings, a series of circularly arranged muffle tubes 1 of relatively thin-walled heat-resistant steel extend generally horizontally but at a slight downward inclination between a front header plate 2 and a rear header plate 3. The tubes open through these header plates and to the front header plate 2 is secured a dome-shaped cover member 4 having a hollow trunnion 5 projecting coaxially outward therefrom. This trunnion is supported on rollers forming bearings 6 mounted on top of a concrete block 7. Similarly, at the opposite, lower end of the cooler a dome-shaped rear cover member 8 is secured to the header plate 3, and this cover member is formed with a coaxially-disposed hollow trunnion 9 supported in a saddle bearing 10 mounted on top of a concrete block 11. A thrust-bearing 12 encircling

the trunnion 9 and interposed between the cover 8 and saddle bearing 10 opposes endwise movement of the cooler within its saddle bearings. The muffle tubes are held in association and mutually supported intermediate their length by a flat ring 13 suitably provided with holes for passing the muffle tubes 1.

The cooler is rotated by any suitable means, for example by an electric motor (not shown) arranged in driving engagement with a ring gear 14 encircling the rear header plate 3 and laterally abutting and fastened to the rear cover member 8. For feeding the hot material to be cooled into the cooler there is provided at the forward end of the apparatus a water-cooled spout 15 leading off at a downward inclination from the bottom of a hopper 16 which desirably is located below the discharge end of a rotary kiln (not shown) for receiving material, for example lime, spilling from the kiln.

The spout extends through the hollow trunnion 5 so as to empty into the compartment provided by the dome-shaped cover member 4 forwardly of the front header plate 2. A closure ring 17 encircling the spout and snugly fitting within the open end of the hollow trunnion 5 seals this inlet compartment against the outside atmosphere.

At the discharge end of the cooler a conical-shaped deflector piece 18 projects centrally rearward from the rear header plate 3 and partially through the hollow trunnion 9. A series of radially disposed vanes 19 occupying the outlet compartment provided by the cover member 8 and rotatable with the cover member, intercept and lift the material issuing from the discharge ends of the muffle tubes and cause it to spill down the surface of the deflector piece and out through the hollow trunnion 9. A discharge casing 20 surrounding the open end of the hollow trunnion 9 includes a chute 21 through which the cooled material escapes from the casing—for example, onto a conveyor (not shown) by which it is carried to a place of storage. A weighted flap valve 22 closes the clearance in the chute passageway above the material therein.

Contained within and extending throughout a portion of the length of the muffle tubes 1 are diaphragm units 23. These diaphragm units, as best illustrated in Figs. 3 and 4, each comprises a pair of elongated metal plates 23a bent at approximately right angles and welded together at their corners, as indicated at 24, to define four radially-disposed diaphragms or wings 25 directed approximately at right angles to each other and dividing the tubes into quadrant-shaped compartments. The diaphragms are provided with relatively large escape openings 26, the openings of adjacent diaphragms being offset in a direction lengthwise of the cooler. The outer longitudinal edges of the diaphragms are adapted to slidably engage and rest upon the inside circumference of the tubes so as to be manually insertible and removable from the tubes. For retaining the diaphragm units in place, they may be tack-welded to the tubes as indicated at 27. The diaphragm units may be made up of several sections assembled end-to-end as indicated in Fig. 4, and for this purpose tongues 27a project from the end of one section and are designed to slip over the opposed end of a contiguous section.

Running lengthwise of and located a short distance below the cooler are a plurality of spray pipes 28, shown in the present instance (Fig. 5)

as three in number but which may be more or less than this, as desired. These spray pipes are arranged parallel to each other and to the tubes, and at one end are connected by a header pipe 30. Opposite ends of header pipe 30 are capped while one end of header pipe 29 is closed and its other end is connected by a conduit 29a to a source of water supply for furnishing water to the spray pipes under pressure. The header pipes 29 and 30 are bent into arcs concentric with the arcuate path of travel of the muffle tubes in completing their down swing and beginning their up-swing during the rotation of the cooler, the location of the spray pipes relative to the tubes being indicated in Fig. 2. The spray pipes are perforated to provide longitudinal rows of orifices 31 from which cooling water is discharged in directions such as to impinge upon the bottom circumferential surfaces of the muffle tubes (see Fig. 2) as the latter sweep through their lowermost arc of travel and subject these tubes to a bath of cooling water.

Arranged below the cooler and extending throughout the length of the spray pipes 28 is a sump 32 into which the water delivered by the spray pipes may drain, and an outlet pipe 33 is suitably provided for removing water from the sump. A shield 34 is secured to the circumferential portion of the header plate 3 at the rear end of the cooler and this shield is cupped so as to direct into the sump 32 the water draining down the muffle tubes. A cover 35 closes a man-hole in the front header plate 2 but this cover may be unbolted from the header plate to afford access to the interior of the ring of tubes.

The operation of the rotary tube cooler just described is as follows: The rotation of the apparatus having been started, the material to be cooled is fed by the spout 5 into the inlet compartment provided by the cover plate 4 at the forward elevated end of the cooler where it flows into the open ends of the muffle tubes 1 and under the combined action of gravity and agitation due to rotation of the cooler passes downwardly within the tubes. After traversing the tubes for a portion of their length, the mass of material encounters the diaphragm units 23 and is split up by these diaphragms into four separate shallow streams each passing into one of the segmental compartments formed by the diaphragms with the circumferential walls of the tubes. During rotation of the cooler the material is showered from one compartment to another by way of the openings 26 in the diaphragms, mixing and tumbling the material about and exposing all parts of it to the cooling surface of the tubes, including the large surface presented by the diaphragms which are in heat-conductive contact with the walls of the tubes.

Throughout the travel of the material through the muffle tubes 1 it is indirectly cooled by the spray pipes 28 during a period in the rotation of the cooler. The spray pipes being located below the cooler and discharging upwardly against the tubes, thus apply water to the areas of the tubes that are at such stage of rotation of the cooler overlain by layers of hot material washing along the inside of the tubes. As the tubes in their rotation move out of the range of the water sprays and complete their circular path of travel, evaporation of moisture from the outside of the tubes takes place, thus accelerating the cooling action. And because this evaporative effect is important for the most efficient opera-

tion of the cooler, the muffle tubes 1 are preferably left uncovered and exposed to the atmosphere in order to promote the free circulation of air into contact with the tubes.

The metal diaphragms not only serve to cascade the material during its downward passage through the tubes, but also function as heat-conducting plates for transferring the heat from the material within the segmental compartments to the walls of the tubes. As will be seen from Fig. 2, not only are the circumferential closing walls of three segmental compartments of each tube subjected to the direct action of the water sprays as the tubes swing through their lowermost arc of travel, but the diaphragms by reason of their snug engagement with the walls of the tubes are indirectly but effectively cooled by the sprays and in this manner substantially contribute to the cooling of the material not only by increasing the cooling area of the tubes but by providing for a more rapid dissipation of heat from the material. Furthermore, because the openings 26 in the diaphragms are staggered relative to each other in a lengthwise direction, the material flowing through the openings in one diaphragm is intercepted by the succeeding diaphragm, thus interrupting the travel of the material between the segmental compartments and causing the material to pause and move a short distance lengthwise along each diaphragm before escaping onto the next diaphragm. This insures a suitable interval of contact between the material and the diaphragms and enhances the cooling effect.

As the cooled material issues from the ends of the muffle tubes, it is directed by the deflector piece 18 out through the hollow trunnion 9 and thence into the discharge casing 20. From the discharge casing the material is led off by way of the chute 21, being at this time sufficiently cool as to be placed immediately into sacks without danger of charring or burning the sacks. Or if desired the material may be moved to a place of storage.

When the diaphragms become worn after repeated use, the weld spots may be cut away with a torch or the like and the diaphragm units with drawn longitudinally from the tubes. Then new units may be slid into the tubes and tack-welded into place.

While it is within the scope of the present invention to utilize air as the cooling medium for the tubes, greatly superior results are attained by employing a liquid coolant, such as water,

5 by reason of its ability to rapidly absorb and carry off heat from the tubes as well as to increase the cooling effect by evaporative action. Also instead of bathing the tubes by means of a spray, the tubes may periodically dip within 10 a tank of cooling liquid, although this is not desirable because it imposes lateral stresses upon the tubes which might result in damage thereto.

15 The diaphragms may be made of heat-resistant steel or other suitable metal or alloy which possesses durability and good heat-conducting properties.

20 It will be understood that the invention may take other forms than that described above, which is to be regarded as exemplary rather than as restrictive of the invention, with departing from the spirit of the invention as defined in the following claim:

We claim:

25 A rotary tube cooler comprising a series of laterally spaced-apart muffle tubes supported in circular arrangement about an axis of rotation which is sufficiently inclined to the horizontal to enable granular material to be cooled to gravitate through the tubes when the cooler is rotated, heat-conductive diaphragm units extending longitudinally and fixed within said tubes for dividing the stream of material flowing down a tube into smaller streams and for imparting agitation thereto, each of said diaphragm units including wall portions meeting at the center of its associated tube and said wall portions having openings therein to allow the material to flow from one compartment into 30 another during rotation of the cooler, and means disposed below the path of rotation of said tubes for delivering an upwardly impinging spray of cooling water against the lower surface of said tubes as said tubes intercept the spray during 35 40 45 rotation of the cooler.
